UNITED STATES PATENT OFFICE.

SAMUEL HARRY NORTON, OF MEADVILLE, PENNSYLVANIA.

GRINDING MACHINE.

Application filed May 4, 1920. Serial No. 378,767.

To all whom it may concern:

Be it known that I, SAMUEL H. NORTON, a citizen of the United States, residing at Meadville, in the county of Crawford and

5 State of Pennsylvania, have invented new and useful Improvements in Grinding Machines, of which the following is a specification.

This invention is designed for rapid 10 grinding of cylindrical surfaces. Broadly speaking it involves a plurality of work-carrying means having an orbital movement through a part of the path of which the grinding operation is accomplished and 15 through another part of which a re-loading of the means is accomplished.

In carrying the invention forward it is desirable to provide means by which the work may be rotated and to have this means 20 provided with devices for varying the speed at which the work is rotated. It is also desirable to vary the speed of the orbital movement of the work-carrying means in different parts of its travel, that is, in that 25 portion of the path in which the grinding is done and in which the work is changed the speed should be comparatively slow and in that part of the travel which is carrying the work-carrying means to the grinding 30 wheel, or in other words, in the intermediate portions of the travel the speed should be comparatively rapid.

Various adjustments for the grinding wheel and for reversing the reciprocating 35 movement thereof and for feeding the wheel are also provided.

Other features of the invention will appear from the specification and claims.

The apparatus of the invention is illustrated in the accompanying drawings as 40 follows:—

Fig. 1 is a plan view of the machine, partly in section.

Fig. 2 and end view of the grinding wheel 45 and driving spindles of the work-carrying means showing their relation.

Fig. 3 is a front elevation of the machine.

Fig. 4 is a section on the line 4—4 in 50 Fig. 1.

Fig. 5 an end elevation of the machine.

Fig. 6 an enlarged plan view of the shifting device for shifting the speed of the travel of the orbital work-carrying means.

Fig. 6^a a detail view of the shift handle.

Fig. 7 a section on the line 7—7 in Fig. 1.

Fig. 8 a section on the line 8—8 in Fig. 1.

Fig. 9 a section on the line 9—9 in Fig. 3.

Fig. 10 is a detail view of the shifting lever for reversing the grinding wheel carriage.

60

Fig. 11 shows a section on the line 11—11 in Fig. 1.

Fig. 12 is a section on the line 12—12 in Fig. 5.

1 marks the base of the machine, 2 the 65 shaft on which the work carrying means is mounted, and 2^b bearings in which the shaft 2 is journaled. Heads 3 and 4 are mounted on the shaft 2. The head 4 carries the centers 5. The centers are carried in the usual 70 spindles 6—6 in the tail stock and adapted to be adjusted by any convenient mechanism (not shown) secured by the clamps 7. The centers 8 are arranged in the spindles 9 of the head stock on the head 3 and the spindles 75 9 are rotated and provided with any convenient means for rotatively driving the work. The spindles 9 are carried in bearings 10 preferably ball bearings in the head 3 and they are provided at their rear ends 80 with gears 12 (see Figs. 1 and 4). The gears 12 mesh with gears 13 carried by rock arms 14, the rock arms being secured to the head by means of pins 15. Arms 16 on the rock arms are provided with cam rollers 17 85 which engage a cam 18 in a case 11. Springs 19 throw the rock arms to carry the gears 13 outwardly and the rollers 17 operate on a surface 20 within the case 11 except where actuated by the cam 18. During the part of 90 the travel in which the roller 17 is on the cam 18 the gear 13 is forced into mesh with a gear 21 journaled on the shaft 2. The gear 21 is driven by a gear 22 carried by a short shaft 23 which is journaled in 95 bearings 24. A gear 25 is fixed on the shaft 23 between the bearings 24 and meshes with a gear 26 (see Fig. 9). A gear 26 is fixed on a shaft 27. The shaft 27 is journaled in bearings 28 in the frame. A gear 29 is 100 slidingly mounted on the shaft 27 but locked against rotation thereon by a spline 30. A floating gear 32 is carried by a frame 31 which slides with the gear 29. The gear 32 is mounted on a pin 33 in the frame 31 105 and is adapted to be thrown into mesh with any of the gears 36 which gears vary in size. The gears 36 are mounted on a shaft 37, the shaft 37 being journaled in bearings 38 in the frame. The frame 31 may be 110 thrown to different positions so as to engage the various gears 36 by means of the handle

34 which may be locked into the varying notches 35, thus accomplishing a variation in speed of the gear 26 and consequently of the rotation of the spindle 9. This speed changing device is one of ordinary construction and quite commonly used on machine tools. The largest of the gears 36 meshes with a gear 39 mounted on a shaft 40 (see Fig. 12) and is fixed on the shaft by means 10 of a pin 41. The shaft is mounted in the frame by bearings 42. A gear 43 is mounted on the shaft 40 and meshes with a gear 44. The gear 44 is mounted on a shaft 45 extending lengthwise of the machine 15 and mounted in bearings (not shown) on the frame. A gear 46 is fixed on the shaft 45 and meshes with a gear 47. The gear 47 is fixed on a shaft 48 carried in bearings 49 mounted on the frame. A pulley 50 is fixed on the shaft 48. A belt 51 drives the pulley from the pulley 52. The pulley 52 is fixed on a shaft 53. The shaft 53 is mounted in bearings 53^a on an upright 53^b extending upwardly from the frame. A chain gear 54 is mounted on the shaft 53 and a chain 55 extends from the gear 54 to a gear 56. The gear 56 is mounted on a rotor shaft 57 of a motor 58. The motor is mounted on a base 59 carried by 30 the post or frame 53^b. Through this chain of mechanism it will be readily seen that the spindles 9 are driven from the motor and may be given varying speeds through the speed changing device as desired and that 35 this rotation is accomplished notwithstanding the orbital movement of these spindles.

Orbital movement is given to the spindles through the following driving mechanism which as before stated preferably varies the 40 movement so that in that part of the travel in which the grinding is done and the work is changed the movement is very slow while in the intermediate parts of the travel the movement is very rapid. A worm gear 60 is fixed on the end of the shaft 2. A worm 45 61 meshes with this gear (see Fig. 11) and is mounted on a shaft 62. The shaft 62 is carried in bearings 63 in the frame. Gears 64 and 65 are journaled on the shaft 62 and are adapted to be locked with the shaft by a clutch element 66 which has the detents 67 and 68 which are adapted to be thrown into engagement with similar detents on the gears 64 and 65. The gear 64 forms the 50 slow speed connection. It meshes with a gear 69 journaled on the shaft 40. A worm gear 70 is fixed on the hub of the gear 69 and meshes with a worm 71. The worm 71 is carried by a shaft 72. The shaft 72 is 55 journaled in bearings 73 in the frame. A worm gear 74 (see Figs. 5 and 12) are fixed on the shaft 72 and a worm 75 meshes with the gear 74. It is carried by a shaft 76, the shaft 76 being journaled in bearings 77 60 on the frame. A friction disc 78 is fixed

on the shaft 76 and is engaged by a friction wheel 79. The friction wheel 79 is carried by a shaft 80. The shaft 80 is mounted on bearings 81 and 82 on the frame. A gear 83 is fixed on the shaft 80 and meshes with the gear 43 on the shaft 40. As before described the gear 43 gets its motion from the shaft 45 and through the connection heretofore described with the motor the orbital movement of the spindle is accomplished. 70 This speed may be varied by changing the location of the friction pulley 79 on the friction disc 78. An arm 84 carries the friction pulley 79 and controls its position relatively to the axis of the disc. The arm 84 is slid- 75 ingly mounted on an upright shaft 86 (see Fig. 3) by means of the bearings 87. An arm 88 extends from this bearing through the front of the frame and a locking pin 89 is arranged in the arm 88 and is adapted 80 to be inserted in the openings 90 on the frame so as to lock the friction pulley in its different adjustments to vary the speed at which the spindle is given orbital movement in that part of the path in which the work is accomplished. 85

The intermediate orbital movement of the work-carrying means should be, as before described, rapid and of uniform speed. This is accomplished through the gear 65. 90 This gear meshes with a gear 91 on the shaft 40 and this shaft is driven, as before described, by the gear 43 meshing with the gear 44 on the shaft 45. This completes the drive for this intermediate movement. 95

The shift mechanism for shifting the driving connection to the shaft 62 and consequently to the work-carrying means is as follows: The friction element 66 has a groove 92 which is engaged by the end of the lever 93 in the usual manner. The lever is mounted on a pin 94 carried by the frame. An arm 95 extends from the lever 93 and is pivotally connected therewith by a pin 96. The extension 95 extends through a slot 97 in the cover plate 98 on the housing 35^a, the housing being mounted on the frame (see Figs. 11 and 6). A yielding locking device is provided by a sliding block 98^a arranged on the top of the lever 95 and pressed downwardly by a spring 99, the spring engaging a shoulder 100 on the lever 95. The block has a detent 101 which engages a cam projection 102 secured to the plate 98. A slide 103 is carried by guides 104 in the housing. 105 A cam finger 105 extends forwardly from the slide 103 into the path of a cam 106 carried by the worm gear 60. The position of the finger 105 may be adjusted. The finger 105 is slidably mounted in the slide 103 and 110 may be adjusted by a screw 108 which is provided with a shoulder 109 engaging the rear wall 110 of the slide 103. The screw stem has a shoulder 111 engaging the rear wall of the slide and a handle 112 is provided by means 115 120 125 130

of which the screw may be adjusted. In this way the finger 107 may be retracted or moved forward so as to vary the thrust which is accomplished by the cam 106. A 5 spring 113 extends into a socket 114 in the rear end of the slide and engages a plug 114^a which extends rearwardly into contact with the housing. This spring 113 tends to force the slide into a forward position and consequently throws the clutch to effect the high speed connection. When the cam 106 engages the finger 105 it pushes the slide 103 to the rear. A pin 115 engages the lever 95. This pin extends into a socket 116 in the 10 slide and is pressed outwardly by a spring 117. The yielding engagement of the notch 101 with the cam 102 holds the lever in its forward position until the spring 117 is sufficiently depressed when it overcomes this 15 yielding lock and throws the lever 95 so as to reverse the clutch. The purpose of this yielding detent and the spring pressed pin, therefore, is to carry the clutch across from one engagement to the other and thus prevent the stalling of the device when in neutral position. The lever 95 may be thrown laterally between the guide surfaces 118 into the notch between the plates 118^a so as to lock the clutch in neutral position and thus 20 stop the orbital movement of the work-carrying means entirely.

A grinding wheel 119 is mounted on a shaft 120. This shaft is carried in bearings 121 (see Fig. 1) extending upwardly from the sliding frame for the grinding wheel. A gear 122 is fixed on the spindle 120 between the bearings 121 and meshes with a gear 123. The gear 123 is mounted on a shaft 124 (see Fig. 8). The shaft 124 is carried in bearings 125 on the frame. A pulley 126 is fixed on the shaft 124. A belt 127 extends around the pulley 126 and around a guide pulley 126^a journaled on a shaft 126^b extending upwardly from the grinder frame. The belt 127 extends over a pulley 128 on the shaft 53. It is carried over a tightening pulley 129, the tightening pulley being carried by a shaft 130. The shaft 130 is mounted on a spring actuated arm 131. The arm 131 is carried by a pin 132 extending from the sub-base and the pulley is kept under tension by a spring 133. The belt extends around a pulley 134 mounted on a shaft 134^a on the grinding wheel base and from thence 55 to the pulley 126. It will be readily seen that this system of belts permits the reciprocal movement of the grinding wheel to carry it to locate the work.

The grinding wheel frame 135 has the 60 guide ribs 136 which are carried by the sub-frame 137. The sub-frame 137 is carried by guides 138 on the adjusting frame 139 and is adapted to be moved backward and forward to adjust the feed of the grinding wheel. The adjusting frame 139 has the 65

guide rib 140 which operates in the guide grooves 141 in a table 142 arranged on the base 1. The adjusting frame has a rack 143 along its underside which engages a pinion 144. The pinion 144 is carried by a shaft 70 145 journaled in bearings on the frame and has a hand wheel 146 at its forward end by means of which the adjusting frame may be moved along to any point desired. The purpose of this is to locate the wheel generally 75 with relation to the work, the reciprocating motion being accomplished by the grinding wheel frame.

The sub-frame is moved forward and back to effect the feeding of the grinding wheel 80 by means of the following mechanism: A nut 147 projects from the sub-frame and is engaged by a screw 148. The screw has a stem 149 journaled at 150 in the sub-frame. A worm gear 151 is fixed on the end of the 85 stem 149. A worm 152 meshes with the worm gear 151. The worm is carried by a shaft 153. The shaft 153 is carried by bearings (not shown) on the frame. A gear 154 is fixed on the shaft 153. It meshes with a 90 gear 155 in a shaft 156 (see Fig. 1) running to the front of the machine. A ratchet wheel 157 for providing a micrometer feed is secured to the front end of the shaft 156. It has the usual operating arm 158 which is 95 engaged by a rock arm 159. The rock arm 159 is carried by a shaft 160 and a finger 161 is in the path of cam fingers 161^a on the work-carrying means so that the micrometer feed may be actuated automatically as the 100 work advances.

The reciprocating motion given to the grinding wheel frame is as follows: A cone pulley 162 is fixed on the spindle 120. The belt 163 communicates the movement from 105 the pulley 162 to a pulley 164. The pulley 164 is mounted on a shaft 165 (see Fig. 7). The shaft 165 is mounted in bearings 166 on the frame. A clutch element 167 is slidingly mounted on the shaft 165 and is locked therewith by a spline 168. Clutch elements 169 and 170 are adapted to be engaged by the element 167 alternately. The element 169 is locked with a gear 171 and, therefore, when the clutch element 167 is in engagement with the element 169 the shaft 165 is driven directly by the pulley 164, it being understood that the pulley 164 is journaled on the shaft 165. A gear 172 is locked with the element 170 and meshes with a gear 173. The gear 173 is carried by a shaft 174. The shaft 174 is mounted in bearings 175 and 176 on the frame. The gear 173 meshes with the gear 171. When, therefore, the clutch element 167 is in engagement with the element 170 120 the motion from the pulley 164 is carried by way of the gear 171 through the gear 173 and gear 172 and the clutch to the shaft 165. It will be readily seen that the shaft 165 will 125 be driven in a reverse direction when the 130

clutch element 167 is in engagement with the clutch element 170 from the direction in which it is driven when the clutch element 167 is in engagement with the element 169.

- 5 Motion is delivered to the grinding frame or carriage through the following mechanism: A worm 177 is fixed on the shaft 165. It meshes with a gear 178 on a shaft 179. The shaft 179 is journaled in bearings 180 on the 10 frame. A gear 181 is fixed on the shaft 179 and meshes with a gear 182. The gear 182 is fixed on a shaft 183. The shaft 183 is journaled in bearings 184 on the frame. A gear 185 is also fixed on the shaft 183 and 15 this gear operates in a rack 186 carried by the grinder frame. Consequently as the gears are rotated through the driving mechanism just heretofore described the frame is moved through the action of the gear mechanism 20 on the rack 186.

The clutch is reversed by the following mechanism:—An arm 187 extends into a groove 188 on the clutch element 167. The arm 187 is carried by a shaft 189, the shaft 25 being mounted in bearings 190 in the grinding wheel frame (see Fig. 10). An arm 191 is secured to the shaft 189 (see Figs. 4 and 10) and a spring pressed finger 192 is arranged in the path of the arm 191 so as to 30 yieldingly hold it in one position or other locking the clutch 167 in one of its driving connections or the other. Cables 193 extend from the arm 191 by way of guide pulleys 194, 195 and other pulleys (not shown) to 35 the front of the machine, the cable being carried along the front of the machine as clearly shown in Fig. 3 and being provided with stops 196 and 197 which are adjustably secured to the cable and engage a stop 198 40 on the frame. It will readily be seen that the cable moves with the grinding wheel frame and when one of the stops 196 or 197 engages the stop 198 it overcomes the yielding finger 192 and reverses the clutch, thus 45 reversing the movement of the grinding wheel carriage.

The general operation of the machine is as follows: The work is placed in one of the work carrying means while the work carrying means is in the slow part of its path and during the grinding operation of the companion carrying means. It will be noted that the arc-shaped movement of the work as it is carried forward accomplishes a 50 certain amount of feeding movement which is desirable. As the work approaches the grinding wheel the grinding wheel is reciprocated along the work and the work is rotated through the driving mechanism here- 55 tofore described. After the carrying means has traveled carrying the work past the grinding wheel the orbital movement of the shifting device operates speeding up the rotation of the work carrying means to carry 60 a new piece of work into position relatively

to the grinding wheel and the finished piece of work into position to be removed. In this way the grinding action is not only expedited but the removal of the work may be readily and conveniently accomplished while 70 the grinding operation is taking place.

What I claim as new is:—

1. In a grinding machine, the combination of a grinding wheel; a power-driven work-carrying means having an orbital 75 movement with a path carrying the work to the wheel; and mechanism varying the orbital speed of the means in the part of the path at the wheel from the speed in other parts of the orbital path.

2. In a grinding machine, the combination of a grinding wheel; a work-carrying means comprising a plurality of work securing devices, said means having an orbital path with a path carrying the work to the 85 wheel and to a loading position, one device being in the loading position with another device at the wheel; and mechanism varying the orbital speed of the means in the part of the path with the work at the wheel and 90 in loading position from the speed at intermediate points in the path.

3. In a grinding machine, the combination of a grinding wheel; a power-driven work-carrying means comprising a spindle, 95 said means having an orbital movement with a path carrying the work to the wheel and to a loading position; devices rotating the spindle in the part of the path at the wheel; and means for disengaging said devices in 100 the part of the path at the loading position.

4. In a grinding machine, the combination of a grinding wheel; a power-driven work-carrying means comprising a plurality of spindles, said means having an orbital 105 movement with a path carrying one spindle to a wheel and another spindle to loading position while said first spindle is at the wheel; devices rotating said spindles in that part of the path at the wheel; and means for 110 disconnecting said devices at the loading position.

5. In a grinding machine, the combination of a grinding wheel; a work-carrying means comprising a shaft; a driving means for the 115 shaft; a head carried by the shaft; a spindle carried orbitally by the head; a driving connection for the spindle comprising means concentric with the shaft; and devices disengaging the connection in parts of the 120 travel of the spindle away from the wheel.

6. In a grinding machine, the combination of a grinding wheel; a work-carrying means comprising a shaft; a driving means for the shaft; a head carried by the shaft; a spindle 125 carried orbitally by the head; a gear connection for the spindle comprising a gear on the spindle; a gear on the shaft; a floating intermediate gear; and devices throwing the intermediate gear into and out of mesh with 130

one of the other gears to break the connection in parts of the travel of the spindle away from the grinding wheel.

7. In a grinding machine, the combination 5 of a grinding wheel; a work-carrying means comprising a shaft; a driving means for the shaft; a head carried by the shaft; a spindle carried orbitally by the head; a gear connection for driving the spindle comprising a 10 gear on the spindle; a gear on the shaft; an intermediate floating gear; a movable mounting for the intermediate gear carried by the head; and devices acting on the mounting as the head rotates throwing the 15 intermediate gear into and out of mesh with one of the other gears to make and break the driving connection to the spindle at the grinding wheel and other parts of the path respectively.

20 8. In a grinding machine, the combination of a grinding wheel; a work-carrying means comprising a shaft; a driving means for the shaft; a head carried by the shaft; a plurality of spindles carried orbitally by the 25 head and disposed to locate one spindle in loading position as another spindle is at the wheel; a driving connection for the spindles comprising means concentric with the shaft; and devices disengaging the connection at 30 the loading position.

9. In a grinding machine, the combination 35 of a grinding wheel; a work-carrying means comprising a shaft; a driving means for the shaft; a head carried by the shaft; a plurality of spindles carried orbitally by the head and disposed to locate one spindle in loading position as another spindle is at the wheel; a driving connection for the spindles; devices disengaging the connection at 40 the loading position; a gear connection for driving said spindles comprising gears on the spindles; a gear on the shaft; intermediate floating gears between the gears on the spindle and the shaft; and means for throwing 45 said intermediate gears into and out of mesh with the other gears of its train to make the driving connection with the spindle at the wheel and to break the driving connection with the spindle at the loading 50 position.

10. In a grinding machine, the combination 55 of a grinding wheel; a work-carrying means comprising a spindle having an orbital movement with a path carrying the work to the wheel; mechanism for varying the orbital speed of the means in the part of the path at the wheel from the speed in other parts of the path; devices rotating the spindle in that part of the path of the spindle 60 at the wheel; and means for disconnecting said devices in other parts of the path.

11. In a grinding machine, the combination 65 of a grinding wheel; a work-carrying means comprising a plurality of rotating spindles having an orbital movement with a

path carrying the work to the wheel and to a loading position; mechanism varying the orbital speed of the means with one spindle at the wheel and another at the loading position from the speed in intermediate portions of the path; devices for rotating the spindles; and means for disengaging said devices at the loading position. 70

12. In a grinding machine, the combination 75 of a grinding wheel; a work-carrying means having an orbital movement with a path carrying the work to the wheel; devices giving to the orbital movement a slow speed at the grinding position and a fast intermediate speed; and means for varying the low speed. 80

13. In a grinding machine, the combination 85 of a grinding wheel; a work-carrying means having an orbital movement with a path carrying the work to the wheel; devices giving to the orbital movement a slow speed at the grinding position and a fast intermediate speed; and means for varying the low speed comprising a friction driven speed changing device. 90

14. In a grinding machine, the combination 95 of a grinding wheel; a rotating head; a work-carrying means on the head having an orbital movement carrying the work to the wheel; a driving mechanism for the head comprising a fast speed connection and a slow speed connection; and a shift device automatically throwing said connections into and out of operative position to vary the speed of the head giving the head a slow speed at the wheel and a high speed away from the wheel. 100

15. In a grinding machine, the combination 105 of a grinding wheel; a rotating head; a work-carrying means on the head having an orbital movement carrying the work to the wheel; a driving connection for the head comprising a fast speed connection and a slow speed connection; a shift device automatically throwing said connections into and out of operative position to vary the speed of the head giving the head a slow speed at the wheel and a high speed away from the wheel, said device comprising a lever for shifting said connection; and a cam on the head acting on the lever. 110

16. In a grinding machine, the combination 120 of a grinding wheel; a rotating head; a work-carrying means on the head having an orbital movement carrying the work to the wheel; a driving connection for the head comprising a fast speed connection and a slow speed connection; a shift device comprising a cam on the head; a clutch mechanism for throwing in and out the high and low speed connections; a lever actuating said clutch; a spring throwing said lever to set the clutch with one connection; a yielding connection between the lever and the cam for throwing the lever in the opposite direction to set the clutch with the other driving 125 130

- connection; and a yielding lock holding the lever against said spring-pressed movement until the spring of the spring connection is sufficiently tensioned to carry the lever 5 through the movement to reverse the clutch.
17. In a grinding machine, the combination of a grinding wheel; a rotating head; a work-carrying means on the head having an orbital movement carrying the work to the 10 wheel; a driving connection for the head comprising a fast speed connection and a slow speed connection; a shift device comprising a cam on the head; a clutch mechanism for throwing in and out the high 15 and low speed connections; a lever actuating said clutch; a spring throwing said lever to set the clutch with one connection; a yielding connection between the lever and the cam for throwing the lever in the opposite 20 direction to set the clutch with the other driving connection; a yielding lock holding the lever against said spring-pressed movement until the spring of the spring connection is sufficiently tensioned to carry the 25 lever through the movement to reverse the clutch; and means for holding the lever in a neutral position.
18. In a grinding machine, the combination of a grinding wheel; a work-carrying 30 means comprising a shaft; a head on the shaft; a work-securing device on the head; a shaft driving the head; two gears journaled on the shaft; a reversing clutch between the gears; a lever for throwing the 35 clutch; a slide through which the lever extends; a spring pressing the slide to throw the lever in one direction; a cam finger on the slide arranged in the path of the cam on the head; a spring carried by the slide and 40 pressing the lever in a reverse direction; and a yielding lock holding the lever against movement until the spring pressing the lever has sufficient tension to swing the lever sufficiently to reverse the clutch.
- 45 19. In a grinding machine, the combination of a grinding wheel; a horizontal spindle for the wheel; a gear on the spindle; a gear meshing with the gear on the spindle; a vertical shaft on which the last-mentioned 50 gear is mounted; a pulley on said shaft; a sliding carriage on which the spindle and shaft are mounted; a belt driving the pulley; a deflecting pulley for the belt; and a 55 tightener taking up the belt to accommodate the carriage movement.
20. In a grinding machine, the combination of a grinding wheel; a work-carrying means having an orbital movement with a path carrying the work to the wheel; and 60 devices actuated by said means for automatically feeding the wheel forward.
21. In a grinding machine, the combination of a grinding wheel; work carrying means comprising a plurality of work 65 curing devices; means having an orbital

movement with a path carrying the work on each device to the wheel; and devices actuated by said means for feeding the wheel forward.

22. In a grinding machine, the combination of a grinding wheel; work-carrying means having an orbital movement with a path carrying the work to the wheel; and feeding mechanism for the wheel comprising a micrometer adjusting device and an 70 operating element for actuating the feeding mechanism arranged in the path of a moving part of the work-carrying means and operated with said work-carrying means.

23. In a grinding machine, the combination of a grinding wheel; a work-carrying means having an orbital movement with a path carrying the work to the wheel; and a feeding mechanism for the wheel comprising an operating element actuating the feeding mechanism arranged in the path of a 80 moving part of the work-carrying means.

24. In a grinding machine, the combination of a grinding wheel; power-driven work-carrying means having an orbital 90 movement with a path carrying the work to the wheel; and means for changing the axial relation of the wheel and means.

25. In a grinding machine, the combination of a grinding wheel; power-driven 95 work-carrying means comprising a plurality of work-securing devices; said means having an orbital movement with a path carrying the work on each device to the wheel; and means for changing the axial 100 relation of the wheel and means.

26. In a grinding machine, the combination of a grinding wheel; power driven work-carrying means having an orbital movement with a path carrying the work 105 to the wheel comprising a rotary spindle adapted to rotate the work; and means for changing the axial relation of the wheel and means.

27. In a grinding machine, the combination of a grinding wheel; power-driven 110 work-carrying means comprising a plurality of rotary spindles adapted to rotate the work, said means having an orbital movement with a path carrying the work to the 115 wheel; and means for changing the axial relation of the wheel and means.

28. In a grinding machine, the combination of a grinding wheel; a power-driven 120 work-carrying means having an orbital movement with a path carrying the work to the wheel; mechanism varying the orbital speed of the means in the part of the path at the wheel from the speed in other parts of the orbital path; and means for changing 125 the axial relation of the wheel and means.

In testimony whereof I have hereunto set my hand.

SAMUEL HARRY NORTON.
